UNITED STATES PATENT OFFICE.

MORRIS TRATTLER, OF NEW YORK, N. Y., ASSIGNOR TO GEORGE FREYDBERG, HERMAN FREYDBERG, AND ETHEL FREYDBERG, COPARTNERS TRADING AS G. H. & E. FREYDBERG, OF NEW YORK, N. Y.

DESIGN FOR A DISPLAY-STAND.

50,085.

Specification for Design.

Patented Dec. 19, 1916.

Application filed April 3, 1916. Serial No. 88,726. Term of patent 14 years.

To all whom it may concern:

Be it known that I, MORRIS TRATTLER, a citizen of the United States, and a resident of the city, county, and State of New York, have invented a new, original, and ornamental Design for Display-Stands, of which the following is a specification, reference being had to the accompanying drawing, forming part hereof.

I claim:

The ornamental design for a display stand, as shown.

MORRIS TRATTLER.
